UNITED STATES PATENT OFFICE

AUGUST JIPP, EHRHARD ROSSBERG, AND EBERHARD HETTLER, OF BERLIN-SIEMENS-STADT, GERMANY, ASSIGNEES TO SIEMENS & HALSKE, AKTIENGESELLSCHAFT, OF SIEMENSSTADT NEAR BERLIN, GERMANY, A CORPORATION OF GERMANY

SECRET TELEGRAPH SYSTEM

Application filed July 16, 1931, Serial No. 551,206, and in Germany July 17, 1930.

Our invention relates to a telegraph system for the secret transmission of messages.

The main object of our invention is to provide in the telegraph traffic an improved system for the secret transmission of messages.

Another object of our invention is to provide special kinds of coding or ciphering.

A further object of our invention is to provide a double coding of a special kind by which an unauthorized deciphering of the coded message is rendered difficult.

A still further object of our invention is to apply the improved secret telegraph system to such apparatus which is equipped with a substantially mechanically operating receiver which cannot be made use of for decoding.

A still further object of our invention is to provide special improved constructions of coding and decoding apparatus.

In telegraph apparatus particularly of the start-stop type, the sign to be telegraphed is translated into a combination of electric impulses which is then electrically transmitted. By operating keys of a keyboard of the transmitter selector bars are in a mechanical manner adjusted in such a way that they are displaced in the direction of their length by a certain amount. These selector bars control the contacts assigned to the individual impulse elements of the sign combination. According to the position of these contacts a circuit is either broken or made by the individual impulses, or each individual impulse is represented either by a positive or negative rush of current. The contacts adjusted by the combination or selector bars are in succession tapped by a suitable contact mechanism and the combination of impulses dispatched thereby.

It is known in start-stop secret printing telegraphs to change the combination of impulses set at the transmitter by a code mechanism before the individual elements of the sign are in known manner successively tapped off the transmitting contacts and to transmit at the receiving side the arriving sign elements across contacts to a decoding mechanism of the receiving apparatus set according to the position of the transmitter code mechanism. This arrangement has the dis-

advantage that in consequence of the code remaining the same there is no sufficient safety against unauthorized decoding.

According to our invention a mechanism is provided for coding which changes its adjustment during the transmission of the signs, and by which the current values of the individual impulses of the sign combination are changed before dispatch and/or the sequence of the dispatch of the individual combination elements is interchanged.

The coding mechanism consists of sets of springs by the operation of which the coding is effected and code discs which control the said sets of contact springs.

These code discs may, for instance, be cams of any suitable design which are either rotatable on a common axis or shaft, or they may be connected by means of a ratio gear so as to have different relative speeds. By providing a number of such different interchangeable disc arrangements other new code systems may be interposed at will which according to laws of their own code every sign differently.

The drive of these code arrangements may likewise be chosen differently by providing either a purely mechanical or also an electro-mechanical driving possibility. A fresh setting of the entire arrangement according to definite characteristics, for instance by means of a code, in certain intervals presents the possibility of varying the code still further.

At the receiver the signals transmitted by the transmitter are across the contacts conveyed to a decoding mechanism operating and set according to the transmitting code equipment or to the receiving relay of the telegraph apparatus according to the nature of the receiver, whereby the secret combination is decoded.

A special advantage of our invention resides in the fact that the decoding at the receiver is effected by means of a mechanism which by its suitable construction according to the nature of the telegraph apparatus employed may either be directly incorporated into the apparatus, since parts of the decoding mechanism may also be directly em-

ployed for the translation of the signal combinations into the sign to be printed, or parts of the standard receiver may be made use of for the decoding, which is mainly applicable 5 for electrically operating apparatus. If this is impossible, as for instance in the case of apparatus operating with mechanical translators, our improved decoding mechanism is simply connected ahead of or in series 10 with the receiver without the necessity arising to make an alteration in it and at the receiver.

Another advantage and novel application 15 of the equipment as represented by our improved decoding mechanism, consists in employing such an equipment also for the purpose of letting a transmitter cooperate with a receiver which is not adapted to the same telegraph alphabet. The further details, 20 advantages and characteristics of our invention will be more fully described with reference to the drawings affixed hereto and forming part of our specification.

It will be readily understood that the embodiment illustrated is only one of many examples of carrying out our invention, and that our invention extends to all changes and modifications of the general arrangement and the details which will suggest themselves 30 to those skilled in the art.

In the drawings

Fig. 1 is a diagrammatic representation 35 of a transmitting apparatus known per se combined with a coding mechanism according to our invention. Of the transmitter only the details cooperating with the coding mechanism are shown,

Fig. 2 represents the apparatus at the receiving end, and more particularly a decoding mechanism connected ahead of or in series with the receiver of known design,

Figs. 3 and 4 represent in principle the changes of the contact sets of a special interchanging arrangement.

Referring to Fig. 1 of the drawings T is the keyboard of a standard start-stop printing telegraph apparatus as described in the "Text Book of Telegraphy" by A. E. Stone published by Mac Millan and Co. Ltd. (London 50 1928) on pages 288 to 293. Below the keyboard are located the selector bars 1 to 5, which on depressing a key lever, for instance the key lever Te shown, are shifted towards one side or the other in accordance with the 55 combination of signals in question. In contrast with the above mentioned telegraph apparatus the signal key mechanism of which operates on a mechanical principle, these selector bars actuate or shift the contacts or switches k_1 to k_5 in engagement with them directly, whereupon on rotation of the simultaneously started tapping cam shaft these contact positions are electrically tapped. The teeth cut into the selector bars 60 are only shown by way of illustration. In

addition to these 5 selector bars there is provided a bar 6 arranged in a similar manner which on depressing a key lever is shifted in one direction only and in doing this closes the contact ak . Across this contact a starting circuit for the starting relay AR is completed which across its contact ar_2 energizes the magnet AM of the start-stop coupling AK so that the start-stop shaft SW with the tapping discs F_1 to F_7 for tapping the adjusted combination of signals performs one revolution. The start-stop coupling AK couples the shaft SW with the continuously revolving shaft MW which through a worm gear is connected with the driving motor of 80 the telegraph apparatus.

The contacts k_1 to k_5 operated by the selector bars are designed as shift contacts and are by means of the upper and lower contact springs connected with further contacts 1_t to 5_t designed as double shift contacts which are adapted to be operated by a special cam arrangement. This cam arrangement is in Fig. 1 designated by the reference character CT and serves to bring about the interchange of the impulse values of a combination set by the selector bar arrangement T. Of the cams N_1 , N_2 and so on controlling these contacts we have, for the sake of clearness, only shown those for the shift contacts 1_t and 2_t , which correspond with the first and second sign elements of a combination of letters. These cam discs N_1 , N_2 and so on are dissimilar and provided with different numbers of cam faces which, furthermore, are irregularly distributed over the periphery of the discs. They are stepped forward by different angles of rotation in correspondence with the pitch of their cam faces or teeth in relation to one another so that a very long interchange period may be attained. These different angles of rotation are obtained by different transmission ratios of the driving wheels R_1 , R_1' , and R_2 , R_2' and so on. The drive of this cam disc arrangement and the resetting of the various discs takes place according to the start-stop principle in dependence on the dispatch of the individual signs, by the stepping magnet FM of the start-stop coupling FK being energized after each dispatch of a combination of signs or signals, so that the driving shaft A is coupled with the continuously rotating motor shaft MW and the shaft AW of the cam disc arrangement is advanced through a corresponding angle by the ratio gear R and R'.

The contacts 1_t to 5_t controlled by the cam discs N_1 , N_2 and so on are with the tips of their contacts connected to a common double battery BA so that the potential of the contacts k_1 to k_5 to be adjusted by the selector bars is changed according to the setting of the t -contacts and a variation of the current 120 125 130

values of the set signal combination is attained.

The contacts k_1 to k_5 are with their central springs connected to the operating means of the interchanging or jumbling mechanism CW by lines l_1 to l_5 . By this contact arrangement the individual conductors of the impulse elements are interchanged with one another so that a variation in the sequence of the various elements of a combination is obtained. For the interchange of two conductors with each other there is provided a set of contacts consisting of two shift contacts, whereby one conductor takes the place of the other and vice versa on reversing the contacts. The number of these sets of contacts follows from the interchange possibilities of the 5 conductors of a five impulse combination.

In Figs. 3 and 4 there are diagrammatically shown examples for the number and for the arrangement of the sets of contacts of such an interchange arrangement. Only the set of contacts $1w$ corresponding with the set of contacts $1w$ of Fig. 1 is shown in detail, the further sets of contacts needed for the interchange of the other conductors being only indicated by squares, for the sake of lucidity of the drawings. The normal position of a set of contacts, i. e. the position in which the continuous conductors are not interchanged, is in Fig. 3 shown by the parallel course of the lines indicating the connection. The crossing of two conductors indicated in broken lines characterizes the interchange of the same and thus corresponds with the position of a set of contacts in the thrown-over state. By this arrangement shown in Fig. 3 all the interchange possibilities of a five conductor system can be covered, only ten contact sets of the type shown at $1w$ being required. They are designated as $1w$ to $10w$. In Fig. 4 there is illustrated a further principle for obtaining

all the interchange or permutation possibilities with only ten sets of contacts. The normal position of a set of contacts is indicated by the crossing lines and the interchanging position by the broken lines representing the parallel course of the connecting conductors. This representation of the principle also shows that a certain conductor, for instance the conductor 1 in Fig. 3 can only be interchanged with conductors immediately adjacent to it in the impulse sequence, for instance with the conductors 2 and 5 by the contact sets $1w$ and $6w$.

In the principle illustrated in Fig. 4, on the other hand, any one conductor is connected with all further conductors of the combination by a single contact operation at a time. By a simultaneous and selective operation of a plurality of such sets of contacts the most diversified exchange possibilities may be brought about.

In Fig. 1 of the drawings only 2 sets of contacts are illustrated for the sake of simplicity and clearness which are connected according to the interchange principle of the Fig. 3 described above and which are identical with the sets of contacts $1w$ and $6w$ of the same figure. Across the sets of contacts $1w$ are thus taken the connecting conductors l_1 and l_2 which can be interchanged one with the other by throwing-over this contact towards the left. In the position shown the contact 4 is closed across which is taken the conductor l_1 ; in exactly the same manner there is closed the contact 2 for the conductor l_2 ; on interchanging these two conductors the contact 4 is opened for the conductor l_1 , for instance, so that now this conductor takes the place of the conductor 2 across the closed contact 1 and vice versa the conductor l_2 takes the place of the conductor 1 across the closed contact 3. The set of contacts $6w$ is shown in a position in which the conductor l_1 is interchanged with the conductor l_5 . As already explained in connection with the set of contacts $1w$, the conductor l_1 passes across the closed contact 1, while the conductor l_5 by the connection of the closed contact 3 takes the place of the conductor l_1 .

The sets of contacts of this arrangement CW are controlled by cams, for instance Nw_1 for the set of contacts $1w$ and Nw_6 for the set of contacts $6w$, which are designed in a similar manner to the cams of the arrangement CT described above.

They are operated by the same driving shaft AW, different angles of rotation for the cams being again obtained for the various transmission ratios. With the resetting of the contact arrangement CT there is thus also simultaneously reset the control arrangement CW in dependence on the start-stop coupling FK.

Across the contacts of this arrangement CW are passed on the connecting conductors l_1 to l_5 to the contacts sk_1 to sk_5 of the transmitting cam shaft SW, which, as already described, is rotated every time a combination of signals is dispatched. These contacts sk_1 to sk_5 are operated in succession by the cams F_1 to F_5 which corresponds with the mechanical keying in the above described telegraph apparatus. The transmitting relay SR connected to these contacts passes the impulses by means of its contact sr on to the line L working with closed circuit.

The arrangements of the receiving apparatus illustrated in Fig. 2 correspond substantially with the arrangements shown in Fig. 1, particularly as regards the coding arrangement. The arriving coded signals are taken up by the receiving relay CER and passed on by its contact cer . On arrival of the starting impulse the cam shaft F

is released in known manner, in consequence of the shaft F being coupled with the motor shaft MW for one revolution by energization of the magnet AMF of the start-stop coupling AFK. Under the control of the contacts ek_1 to ek_5 of the receiving cam shaft, the impulses are first passed across the contacts dw of the de-interchanging device DCW and then in correspondence with their original sequence passed on to the arrangement DCT in which the changes of the impulse values of the individual elements of the signals are neutralized again.

The contacts of the arrangement DCW 15 are controlled by the cams NW (Nw_1 to Nw_{10}), the contacts of the arrangement DCT by the cams N (N_1 , N_2 and so on) in correspondence with the control by the respective cams at the transmitting end. These 20 cams are intermittently advanced by means of a common driving shaft AW, as at the transmitting end, different speeds for the cams being attained again by different transmission ratios of the driving wheels. A

25 resetting also takes place after receipt of a combination of signs or signals. The cams which correspond in the transmitting and receiving apparatus are, as regards their cam faces and their stepping speed, exactly identical so that after prior coinciding adjustment there exists always the same position of the contact in the individual contact arrangements. In this way the double coding caused in the transmitting apparatus is 30 neutralized again in the receiving apparatus.

It is to be particularly noted that the individual connecting conductors l_1 to l_5 (Fig. 2) corresponding with the individual impulse elements must traverse the sets of contacts of the arrangement DCW in the reverse order or mirror reading, as compared with the sequence in the transmitter. Across the contacts of the arrangements DCW and DCT are now charged the condensers C_1 to 45 C_5 provided for the impulse elements in the sense of the non-coded impulse combinations. This arrangement acting as impulse register or storing device, so to say, is tapped element by element immediately after receipt 50 of the five impulse units across the contacts ek'_1 to ek'_5 , which are shortly before or at the completion of a combination of signals closed simultaneously by the cams F'_1 to F'_5 .

The polarized relays R_1 to R_5 are thereby 55 set in correspondence with the non-coded impulse combination, so that their contacts r_1 to r_5 represent the impulse combination set for the first time by the keyboard. Simultaneously a further tapping cam shaft G is 60 started after completion of the revolution of the receiving cam shaft F, by the magnet AMG, of the start-stop coupling AKG, being again excited across the contact ek_7 . By coupling the shaft G with the same motor shaft MW for one revolution the contacts

65 gk_1 to gk_5 controlled by the cams G_1 to G_5 are closed in succession whereby the shortly before adjusted contacts r_1 to r_5 of the polarized relays are electrically tapped. Thus the non-coded combination of impulses of the signal 70 to be transmitted passes to the receiving magnet EM of the associated receiving and printing apparatus. Of this receiving system of the telegraph apparatus there is in Fig. 2 merely illustrated the receiving magnet EM; 75 further details about the translation of the combination of signs and about the printing process itself in case of a sign may be obtained by reference to the literature mentioned above. 80

The release for a resetting of the coding and decoding mechanism in the transmitter and the receiver may preferably take place already during the time of the fifth impulse, so that only a small loss of time is caused by 85 the coding of the combination. It is by no means necessary that all the five impulse elements of a combination be made use of for the coding, if it is desired to avoid a shortening of the transmitting and receiving time 90 for a signal or sign.

The transmission of a sign consisting of a five impulse combination by the arrangements illustrated in Figs. 1 and 2 will now be briefly described: assuming the position 95 of the arrangements CT and DCT and the arrangements CW and DCW corresponds in the transmitter and the receiver with the normal position or a corresponding position taken arbitrarily from the continuous code, 100 which causes a change of the first element of the sign and an interchange of the first with the fifth element. The contacts 1_t ($1dt$) of the arrangement CT (DCT) and the contacts $6w$ ($6dw$) of the interchange arrangement 105 CW (DCW) in the transmitter and receiver are thus reversed while all other contacts are in the assumed normal position. If now on depressing the key lever Te (Fig. 1), which, for instance, sets the impulse series characterizing the letter $c = + - + + +$ by means of the selector bars 1 to 5 and their contacts k_1 to k_5 , this combination is changed by the coding arrangement CT in so far as the impulse value of the first sign element is reversed so that a sign combination 110 $- + + + = Wr$ is produced which corresponds with the return motion of the carriage for page printers. This combination will furthermore in the interchange arrangement CW be subjected to such a change that by the reversed contact $6w$ the first impulse element in the sequence is interchanged with the fifth element, wherefrom now follows the 115 combination $- + + - = x$. This combination is now at last passed on to the tapping contact sk_1 to sk_5 so that the transmitting relay SR transmits the code sign x on to the line. 120 125 130

- the original impulse combination $+-$
 $+++=e$. Shortly afterwards the cam F_7
 will complete a circuit for the coupling mag-
 net AMG, so that now the further tapping
 shaft G is rotated. To the receiving magnet
 EM, which in the inoperative state was kept
 energized across the battery RB and the
 closed contact gk_6 impulses of the original
 combination are supplied during the rota-
 5 tion of this shaft G under the control of the
 cams G_1 to G_5 operating the contacts gk_1 to
 gk_5 , by tapping the contacts r_1 to r_5 . The
 receiving magnet EM will thus print the
 letter e.
- 10 15 Simultaneously with the coupling of the
 tapping shaft G a circuit for the coupling
 magnet FDM was completed across the con-
 tact ek_1 , so that by the response of the cou-
 pling FDK the cams N_1 , N_2 and so on, Nw_1 ,
 20 Nw_2 and so on driven in unison are reset in
 the well known manner.

We claim as our invention:

1. In a telegraph system, a transmitting
 arrangement which contains in combination
 25 an arrangement for setting electric current
 combinations of the signs to be transmitted,
 a coding arrangement adapted to change its
 setting during the transmission of the sign
 in order to code the set electric current com-
 30 binations by direct means, without the inter-
 position of relays, before the dispatch of the
 sign combinations commences, said coding
 arrangement including a plurality of contact
 35 elements corresponding to the impulse ele-
 ments of the sign combinations, separate con-
 trol means for the individual contact ele-
 ments, a common drive for said control
 means, and in cooperation with said trans-
 40 mitting arrangement an arrangement at the
 receiving end containing a contact device
 adapted to pass on the coded arriving im-
 pulses, an arrangement corresponding with
 the coding mechanism at the transmitting
 45 end for decoding the current combinations
 received, and a mechanism in a telegraph ap-
 paratus for the reception and translation of
 the decoded current combinations.

2. In a telegraph system, a transmitting
 arrangement which contains in combination
 50 a keyboard for setting electric impulse com-
 binations of the signs to be transmitted, a
 coding mechanism adapted to change its set-
 ting during the transmission of the telegraph
 signs with means for interchanging the se-
 55 quence of the successive dispatch of the im-
 pulses of the sign combinations set, an ar-
 rangement of contacts adapted to effect the
 dispatch of the impulse combination coded
 60 by the interchange of the impulse elements,
 and in cooperation with said transmitting
 arrangement an arrangement at the receiving
 end containing a contact device adapted to
 65 pass on the coded arriving impulses, an ar-
 rangement corresponding with the coding

mechanism at the transmitting end for de-
 coding the impulse combinations received,
 and a mechanism in a telegraph apparatus
 for the reception of the decoded impulse com-
 binations.

3. In a telegraph system, a transmitting
 arrangement which contains in combination a
 keyboard for setting electric impulse com-
 binations of the signs to be transmitted, a
 coding mechanism adapted to change its set-
 75 ting during the transmission of the telegraph
 signs with means for changing the character
 as well as interchanging the sequence of the
 dispatch of the impulses of the sign com-
 binations, an arrangement of contacts adapted
 80 to effect the dispatch of the coded sign im-
 pulse combinations, in cooperation with said
 transmitting arrangement an arrangement
 at the receiving end containing a contact de-
 vice adapted to pass on the coded arriving
 85 impulses, an arrangement corresponding
 with the coding mechanism at the transmit-
 ting end for decoding the impulse combina-
 tions received, and a mechanism in a tele-
 graph apparatus for the reception of the de-
 90 coded impulse combinations.

4. In a telegraph system, a transmitting
 arrangement which contains in combination
 selector bars adapted to be relatively shifted
 by keys of a keyboard and to control con-
 95 tact assigned to the individual impulses of
 the combination of impulses, said contacts
 by lines connected to means by which the
 code symbols set for the contents controlled
 by said bars are changed in their polarity,
 100 and a contact arrangement adapted to tap
 and dispatch the impulse combinations coded
 by the change of the character of the indi-
 vidual impulses.

5. In a telegraph system, a transmitting
 arrangement which contains in combination
 a contact arrangement adapted to set the
 sign impulse combinations consisting of a
 number of contacts corresponding with the
 110 impulse elements of the sign combinations,
 which is connected to a further contact ar-
 rangement having a number of contacts and
 serving for the dispatch of the impulse com-
 binations, by means adapted to interchange
 115 the connecting conductors of the individual
 contacts of the two contact arrangements
 with each other for the purpose of coding the
 combinations to be dispatched.

6. In a telegraph system a transmitting ar-
 rangement which contains in combination an
 arrangement for setting electric current com-
 binations of the signs to be transmitted, a
 coding arrangement adapted to change its set-
 120 ting during the transmission of the signs,
 which consists of mechanically adjustable
 contact controlling means which code the set
 impulse combinations prior to their dispatch
 by changing the polarity of the individual
 125 impulses and by interchanging the sequence
 of the dispatch of the individual impulses, a

- In this example only the first and the fifth impulse elements have been changed by the coding while the 2nd, 3rd and 4th impulse elements have not been affected by the coding.
- 5 For facilitating the understanding the circuit of the first impulse element of the original combination will now be traced: battery BA-, upper contact 1_t, closed upper contact k₁, connecting conductor l₁, contact 10 4 of the set of contacts 1w, further closed contacts of the sets of contacts not shown of the arrangement CW, closed left-hand contact 1 of the contact set 6w, further contacts of CW, single transmitting contact sk₅, relay 15 SR, battery midpoint MB. The circuit for the fifth impulse element will in corresponding manner pass across the single transmitting contact sk₁ if the further circuits of the remaining impulse elements are tapped by 20 the transmitting contacts corresponding with them.
- The transmitting process briefly takes place as follows: by depressing the key Te 25 the selector bars 1 to 5 are shifted and in addition thereto the bar 6 is moved towards the right whereby the contact ak is closed. A circuit is thus completed across the negative pole, contact ak, relay AR, positive pole, in which the starting relay AR is energized 30 and reverses its contacts ar₁ and ar₂. Across contact ar₂ is then connected the coupling magnet AM, which disengages the locking lever AKH. The pin S detained by the pawl lever KH is then released whereby the coupling discs are coupled with each other. The motor shaft MW drives the cam shaft SW. Simultaneously with the reversing of the ar₁ contact the polarized transmitting relay SR 35 was energized across the negative pole and battery midpoint, so that the starting impulse is sent into the line. The starting impulse is limited by the contact sk₆ which is opened shortly after the start of the transmitting shaft SW.
- 40 The cam faces of the contact discs F₁ to F₅ will now when the transmitting shaft rotates in succession close the contacts sk₁ to sk₅, in order to tap thus the combination indicated above by way of example across the firmly 45 adjusted contacts of the coding arrangements CW, CT and the selector bar arrangement T. Shortly before completion of the revolution of the transmitting shaft SW the cam F₅ will close the contact sk₆ in order to establish 50 thereby a circuit for the stepping magnet of the coding devices. FM releases in the manner described before the start-stop coupling FK so that the driving shaft A and thus also the shaft AW are set in rotation. 55 In this way the cams N₁, N₂ and so on, and also the cam Nw₁, Nw₆ and so on are advanced in correspondence with the pitch of their cam faces and teeth, so that immediately after completion of this sign the contacts of the coding apparatus are set anew. 60
- The impulse combination transmitted by the contact sr in the transmitter is at the receiving end taken up by the receiving relay CER of the decoding device (Fig. 2). With the arrival of the unvarying start impulse 70 the coupling magnet AMF is energized by the reversal of the contact, so that the start-stop coupling AFK couples the receiving shaft F with the continuously rotating motor shaft MW in the manner described before. Shortly after the start of this shaft the contact ek₆ is opened by the advance of the cam F₆, so that the circuit for the coupling magnet AMF is opened and the contact cer becomes disengaged for the now following impulses. As mentioned before the contacts of the coding arrangement DCW and DCT have accurately the same position as the contacts of the coding arrangement in the transmitter and remain stationary 75 during the reception of an impulse combination.
- The incoming impulses of the impulse combination are in succession distributed by the cams ek₁ to ek₅ over the individual connecting conductors l₁ to l₅, which now lead the impulse values across the contacts of the coding arrangement DCW and across the contacts of the coding arrangement DCT, whereby the condensers C₁ to C₅ are correspondingly charged. The impulse coming in first will thus pass across the contact ek₁, conductor l₁, across the contacts of the arrangement DCW not shown, the closed contact 1 of the set of contacts 6dw, whereby it travels to the place of the fifth impulse and now passes on across the contacts dw not shown, the closed contact 2 of the set of contacts 1dw and across the upper contact 5dt of the coding arrangement DCT to the lower plate of the condenser C₅. The upper plate of this condenser is across the lower closed contact of 5dt connected with the midpoint MB of the battery so that in this circuit the condenser C₅ is charged in the sense of the original sign element. In the same way the further condensers are charged by the subsequent impulses. It will be observed 90 that the impulse coming in first charges the condenser C₅ of the fifth impulse element, and that by the further impulses the condensers C₂, C₃ and C₄ and by the fifth impulse the condenser C₁ of the originally first impulse element is charged. Shortly before 95 the completion of the revolution of the receiving cam shaft F the contacts ek'₁ to ek'₅, are closed by the cam F'₁ to F'₅, which occupy the same position, so that the charges of the condensers C₁ to C₅ balance across the 100 polarized relay R₁ to R₅, whereby these relays are set according to the charge of the condensers.
- 105 The relays set their contacts r₁ to r₅ correspondingly so that these contacts represent 110

contact arrangement adapted to effect the dispatch of the coded current combinations and in cooperation with the transmitting arrangement apparatus at the receiving end containing an arrangement which as regards setting and mode of operation corresponds with the coding arrangement of the transmitting end and embodies means for decoding the impulse combinations coded by changes in the polarity of the impulses and by the interchange of the sequence of the dispatch of the impulses, and a mechanism for the reception, for decoding and translating of the combination of signs.

7. In a telegraph system, a transmitting arrangement which contains in combination an arrangement for setting electric current combinations of the signs to be transmitted, a coding mechanism adapted to change its setting during the transmission of signs, which consists of a plurality of cams connected with one another at equal and at different speeds and adjustable by mechanical and electromagnetic driving or coupling means, by which cams are controlled the contacts which are adapted to change the character of the impulses of a set sign combination, an arrangement of contacts for dispatching the coded combinations, and in cooperation with the transmitting arrangement an arrangement at the receiving end which contains apparatus corresponding with the coding arrangement at the transmitting end and contains means for decoding the impulse combinations coded by changing the character of the impulses, and an arrangement for the reception of the decoded sign combinations.

8. In a telegraph system, a transmitting arrangement which contains in combination an arrangement for setting electric current combinations of the signs to be transmitted, a coding mechanism adapted to change its setting during the transmission of signs, which consists of a plurality of cams connected with one another at equal and at different speeds and adjustable by mechanical and electromagnetic driving or coupling means, which cams are provided with different projections or recesses and by which contacts are controlled adapted to change the character of the impulses of a set combination of signs and to interchange the sequence, a contact arrangement for dispatching the coded combinations and in cooperation with the transmitting mechanism an arrangement at the receiving end which contains apparatus corresponding with the coding arrangement at the transmitting end and contains means for decoding the impulse combinations coded by changing the character of the impulses, and an arrangement for the reception of the decoded sign combinations.

9. In a telegraph system, a transmitting arrangement which contains in combination an arrangement for setting electric current combinations of the signs to be transmitted,

a coding arrangement adapted to change its setting during the transmission of signs, two shift contacts each assigned to the first impulses of the sign impulse combinations adapted to be controlled by cams, means for resetting the coding arrangement during the duration of the last impulse for the next sign combination, a contact arrangement consisting of contacts adapted to be in succession operated by cams for tapping and dispatching the coded impulse combinations, and in cooperation with the transmitting arrangement an apparatus at the receiving end containing a contact arrangement adapted to transmit the coded impulses coming in, a mechanism for decoding the current combinations sent and corresponding with the coding mechanism at the transmitting end, and apparatus for receiving the decoded current combinations.

10. In a telegraph system, a transmitting arrangement containing mechanism for setting contacts which are adjusted in the sense of the sign impulse combinations to be dispatched, conductors through which said contacts are connected to a coding device, by which the set contacts are changed in their character, connecting conductors across which the contacts set in correspondence with the sign combinations are connected with the transmitting contacts operated in succession, means consisting of sets of contact springs controlled by cams by which said connecting conductors may be interchanged at will as regards the beginning and end, in order to interchange the sequence of the dispatch of the set impulses of the sign combination for the purpose of further coding, in cooperation with the transmitting arrangement an arrangement at the receiving end which contains a contact arrangement with means for successively transmitting the impulses arriving in succession, means for placing the impulses interchanged in their sequence again into the non-coded sequence, means for decoding the impulses changed in their character, and means for transmitting the impulses in the decoded combination to the receiving mechanism of the telegraph apparatus.

11. In a telegraph system, a transmitting arrangement containing in combination an arrangement for setting electric combinations of the signs to be dispatched, an arrangement adapted to change its setting during the transmission of the signs to code the set electric current combinations, a contact arrangement adapted to effect the dispatch of the coded current combinations, and in cooperation with the transmitting arrangement an arrangement at the receiving end containing contacts adapted to be controlled by a cam shaft, an electric register to which are supplied decoded the coded impulse combinations, an arrangement consisting of such a

number of sets of contact springs each comprising two shift contacts to the middle spring of which are connected the conductors to be interchanged, that all connecting lines across which the contacts controlled by the cam shaft are connected with the register are adapted to be interchanged with one another as regards beginning and end, means for controlling said spring sets for the correct 10 coding, means consisting of two double contacts each for setting the register as regards the character of the non-coded combinations, means for the simultaneous tapping of the register, relays which during the tapping of 15 the register are set in the sense of the non-coded impulse combinations and ensure the reception of the correct sign independent of the setting of their contacts.

12. In a telegraph system, a transmitting arrangement containing in combination an arrangement for setting electric combinations of the signs to be dispatched, an arrangement adapted to change its setting during the transmission of the signs to code the set electric current combinations, a contact arrangement adapted to effect the dispatch of the coded current combinations, and in cooperation with the transmitting arrangement an arrangement at the receiving end containing 25 a contact arrangement for the retransmission of the incoming coded impulse combinations to a decoding mechanism corresponding with the coding mechanism at the transmitting end consisting of two arrangements adapted to be 30 controlled by cams, of which one uncodes the sequence of the impulses, the other the polarity of the impulses of the sign combinations, a register consisting of condensers adapted to be set in the sense of the decoded sign 35 combinations across the decoding mechanism, a number of polarized relays corresponding with the impulse elements of the sign combination and which during the tapping of the register are set in the sense of the decoded 40 sign combination, a contact arrangement adapted to tap the contact of the polarized relays in succession and to transmit the sign combinations to the receiving magnet of the 45 telegraph apparatus, means for operating the contact arrangements during every transmission of a combination of signs, means for resetting the decoding mechanism during the transmission of the signs, means for advancing the cams differing from one another 50 through which the sets of springs of the decoding mechanism are controlled by different amounts in correspondence with the transmitting end, and means for operating simultaneously the contacts of the contact arrangement by which the register is tapped.

13. In a telegraph system, a transmitting arrangement which contains in combination a keyboard for setting electric impulse combinations of the signs to be transmitted, a coding mechanism adapted to change its setting 55

during the transmission of the telegraph signs with means for interchanging the sequence of the successive dispatch of the impulses of the sign combination set, said coding mechanism including a plurality of contact elements corresponding to the impulse elements of the sign combinations, separate control means for the individual contact elements, a common drive for said control means, and in cooperation with said transmitting arrangement an arrangement at the receiving end containing a contact device adapted to pass on the coded arriving impulses, an arrangement corresponding with the coding mechanism at the transmitting end for decoding the impulse combinations received, and a mechanism in a telegraph apparatus for the reception of the decoded impulse combinations.

In testimony whereof we affix our signatures.

AUGUST JIPP.
EHRHARD ROSSBERG.
EBERHARD HETTLER.
